MULTIPLE SWITCH

Walter J. Spengler, Sidney, N. Y., assignor to
Bendix Aviation Corporation, South Bend, Ind.,
a corporation of Delaware

Application September 29, 1934, Serial No. 746,204

3 Claims. (Cl. 200—18)

The present invention relates to a multiple switch and more particularly to a compound ignition switch for selective or simultaneous control of a plurality of internal combustion engines.

5 It is an object of the present invention to provide a multiple control switch which is efficient and reliable in operation while being light and compact in construction.

Another object is to provide such a device 10 which embodies elements for selectively utilizing a plurality of ignition devices for each of a plurality of engines, and for simultaneously rendering all of said devices inoperative at the will of the operator.

15 Another object is to provide such a device which is tightly sealed and efficiently shielded against radio interference.

A further object is to provide such a device in which the shielding is readily removable for inspection or adjustment of the switch without disturbing the wiring harness.

20 Another object is to provide such a device in which the movable switch contacts are pre-tensioned so as to insure effective engagement with the stationary contacts.

25 Another object is to provide such a device which is so designed as to insure proper assembly of the various units, improper assembly being impossible.

30 Further objects and advantages will be apparent from the following description taken in connection with the accompanying drawings in which:

Fig. 1 is a longitudinal section of a preferred embodiment of the device taken substantially on the line 1—1 of Fig. 2;

Fig. 2 is a cross-section taken substantially on the line 2—2 of Fig. 1 and showing the switch units in closed or off position;

40 Fig. 3 is a perspective view showing the switch unit for the center engine in off position and the common grounding switch also in off position;

Fig. 4 is a similar view showing the center switch unit in position to render operative the right magneto and the booster magneto;

Fig. 5 is a similar view showing the switch unit for the center engine in position to utilize the left magneto and the booster magneto, the central common ground switch being open;

50 Fig. 6 is a similar view showing the switch unit for the center engine in position to render operative all three magnetos;

Fig. 7 is an extended view in perspective showing the various parts in their relative operation 55 positions; and

Fig. 8 is a perspective view of the inner side of the terminal block showing the arrangement of the fixed contacts thereon.

Referring first to Fig. 3 of the drawings, it will be seen that the present embodiment of the invention comprises a face plate 1 of suitable material such as cast aluminum having suitable indicia engraved on the outer face thereof or on a name plate 10 suitably affixed thereto. Posts 2 are formed on or suitably fixed to the inner side 5 of the face plate, arranged to support a terminal block 3 in spaced relation thereto. Between the face plate and terminal block a plurality of switch units are mounted, there being here illustrated three such units which are adapted to 10 control respectively the right, center and left engines of a tri-motor power plant.

It will be understood that each engine is provided with two service magnetos and a booster magneto for starting purposes, and each switch 15 unit is intended to render all the magnetos inoperative when in the off position, or to permit the use of either or both service magnetos as desired by the operator, as well as rendering the booster magneto operative in all positions of the 20 switch except the off position. Since the three switch units are identical, a description of one thereof will suffice. It will be understood that the magnetos are rendered inoperative by grounding the primary circuits thereof in the 25 usual and well known manner, so that it is deemed unnecessary to illustrate the magnetos and their circuits inasmuch as these are assumed to be of standard construction.

Referring now more particularly to Figs. 7 and 35 8, it will be seen that the terminal block 3 is provided on its outer side with arcuately arranged groups of terminals 4, 5 and 6 for the left, the booster and the right magnetos respectively of each engine. These terminals extend through 40 the terminal block, and provide fixed contacts 7, 8 and 9 respectively which contacts extend a suitable distance toward the face plate 1 for engagement by the movable contacts of the switch unit. An operating shaft 11 provided with suitable manual operating means 12 is mounted in the face plate 1 opposite each group of fixed contacts. Resilient contact members 13 and 14 are mounted on the operating shaft 11 in predetermined angular relation thereto as by means of 45 50 cooperating D sections 15, 16 and 17 thereof respectively, the contacts being held in assembled position as by means of a nut 18 threaded on the shaft 11. Contact member 13 is provided with four arms 19, 21, 22 and 23 respectively for en- 55

5 engagement with fixed contacts 7 and 9 of the left and right service magnetos, while contact member 14 is formed for engagement with fixed contact 8 of the booster magneto. Contact arms 19,
6 21, 22 and 23 of contact member 13 tend to expand outwardly, and are maintained in suitable position for engaging the fixed contacts 7 and 9 by means of a confining thimble 24 which surrounds the contact member 13 and places the
10 arms thereof under initial stress. Contact 18 tends to contract inwardly toward the axis of the shaft 11 and is maintained in position to engage the fixed contact 8 by means of an annular wall 25 (Fig. 8) formed on the inner side of the terminal block 3.

The switch unit is arranged to occupy four operative positions which positions are defined by a detent and stop plate 26 keyed on the shaft 11 by means of the D section opening 27, and having stop lugs 28 and 29 adapted to engage the sides 30 and 31 of the bearing boss 32 in which shaft 11 is mounted. The plate 26 is also provided with four tapered openings 33, 34, 35 and 36 arranged to be engaged successively by a detent ball 37 received in an opening 38 in the bearing boss 32, and pressed outwardly therefrom by suitable means such as a spring 39 whereby the switch unit is yieldably retained in its various operative positions.

30 Referring to Figs. 2 and 3 of the drawings, it will be seen that when the switch unit is in its off position, the contact arm 22 engages the fixed contact 7 of the left magneto, the contact arm 19 engages the fixed contact 9 of the right magneto, and the contact 14 engages the fixed contact 8 of the booster magneto. Since contacts 13 and 14 are grounded to the body of the switch, which is of course in metallic contact with the frame of the vehicle, it will be seen that the primary circuits of all the magnetos are grounded and the magnetos thereby rendered inoperative.

In Fig. 4 the switch unit of the center engine has been moved to position marked R on the name plate 10, to energize the right service magneto and the booster magneto. It will be seen that this is brought about by the fact that whereas the contact arm 23 now engages the fixed contact 7 of the left magneto, the contact arm 19 is disengaged from the fixed contact 9, and the contact 14 is disengaged from the fixed contact 8 whereby the right service magneto and the booster magneto are rendered operative.

In Fig. 5 this switch unit has been moved to the next position, marked L on the name plate, in which contact arm 21 engages the fixed contact 9 of the right magneto, and contact arm 23 is disengaged from the fixed contact 7 of the left magneto whereby the left magneto and the booster magneto are operative.

80 In Fig. 6 the switch unit has been moved to its final position marked "both" on the name plate in which contact arm 21 is disengaged from fixed contact 9 so that none of the fixed contacts 7, 8 and 9 are grounded whereby all the magnetos are operative.

In case of emergency it is sometimes desirable to quickly render all magnetos of all engines inoperative in order to avoid fire hazard, etc. For this purpose each of the fixed contacts 7, 8 and 9 of all the groups of contacts is provided with a resilient contact 41, 42 and 43 respectively (Fig. 3), all of which resilient contacts extend radially inward toward the axis of the switch, in a single transverse plane as defined by the annular surface 44 of the terminal plate 3, the ends of said

resilient contacts extending inwardly beyond the edge of an axial opening 45 in said terminal block. A reciprocable shaft 46 (Fig. 1) is mounted in a central bearing boss 47 of the face plate 1 and is provided at its outer end with suitable manual operating means 48 and at its inner end with a contact disc 49 suitably fixed thereto as by means of a nut 51 in position to be brought into simultaneous engagement with all the resilient contacts 41, 42, 43 when the shaft 46 is pulled outward by the handle 48. Suitable means in the form of a yielding detent 52 (Fig. 2) is provided in the bearing boss 47 for engaging recessed portions 53 and 54 of shaft 46 to yieldingly retain said shaft in its operative and inoperative positions respectively. 15

The terminal block 3 is fixed to the supporting posts 2 by suitable means such as studs 55 threaded in said posts and provided with hexagonal enlarged sections 56 extending beyond said terminal block. An end plate and cable attachment member 51 is arranged to be mounted on reduced end portions 58 of the studs 55 and is provided with a tapered throat 60 for receiving the end of a conductor cable. Suitable clamping means such as a gland nut 59 is provided for clamping the sheath 61 of the cable harness to the anchoring plate 57. 20 25

The face plate 1 and terminal block 3 are preferably of circular shape as illustrated, and a casing member 62 in the form of a cylindrical cup is provided for completely enclosing and shielding the switch. Casing member 62 has an aperture in its bottom large enough to pass over the nut 59, and is formed to closely fit the end plate 51 as illustrated at 63. As here shown the face plate 1 is provided with an annular shoulder 64 fitting the rim of the casing member 62, suitable packing material 65 being provided in the face plate in order to insure a tight joint. Packing material 66 may also be provided if desired in the end plate 51 to assist in sealing the casing. End plate 51 and casing member 62 are retained in position as by means of nuts 67 on the studs 55.

It will be noted that since the opening in the casing member 62 is large enough to pass over the clamping nut 59, it is merely necessary in order to inspect or service the switch that the nuts 67 be removed whereupon the casing member 62 may be slid back along the cable harness 61 whereupon the entire switch is fully exposed. It will further be noted that by reason of the arcuate location of the terminals in the terminal plate, these may be readily inspected and adjusted when the casing is removed. 55

In order to insure that the terminal block 3 and the end plate 51 be always assembled in proper angular relation to bring the corresponding engine units into registry, the ports 2 of the face plate 1 are spaced slightly unsymmetrically about the axis of the switch instead of being spaced exactly 120 degrees apart. It is thus impossible to assemble the elements except in their proper relationship. 60

In the operation of the device, each of the engine ignition systems may be rendered inoperative, or the various units thereof may be selectively rendered operative by proper manipulation of the rotary switch elements as above described, so long as the master switch handle 42 is in its normal position. When it is desired to render all ignition systems inoperative, it is merely necessary to pull out the master switch handle whereupon all the magnetos are simul- 70 75

aneously grounded and all the engines thereby rendered inoperative.

It will be understood that various changes may be made in the design and location of the parts 5 of the device as illustrated without departing from the spirit of the invention as defined in the claims appended hereto.

What is claimed is:

1. A multiple ignition switch for internal combustion engines comprising a circular face plate, a plurality of groups of axially extending contact members rotatably mounted in said face plate, a terminal block mounted in spaced relation to said face plate, groups of fixed contacts 10 mounted on the inner side of the terminal block extending into the paths of said rotatable contact members, arcuately arranged groups of terminals on the outer face of said terminal block electrically connected to said fixed contacts, 15 an end plate centrally apertured for the reception of a cable harness, mounted in spaced relation to the terminal block, means on said end plate for anchoring a cable thereon, and a casing member in the form of a cup apertured and 20 formed to fit over and seal against said face plate and end plate and completely enclose the switch, the aperture in the casing member being sufficiently large to enable removal of the casing member without disturbing the cable harness. 25
2. A multiple ignition switch comprising a face plate, a plurality of contact members rotatably supported by said plate, a terminal block mounted 30

in spaced relation to said plate, fixed contacts mounted on one side of said block for engagement by said contact members, terminals on the other side of said block electrically connected to said fixed contacts, an end plate mounted in spaced relation to said terminal block and having an aperture therein, means for connecting a cable harness to said end plate in registry with said aperture, and a cup-like casing member formed to engage said face and end plates and completely enclose said contact members, fixed contacts and terminals, said casing member having an aperture therein sufficiently large to enable the removal thereof without disconnecting the cable harness. 15

3. An ignition switch comprising a face plate, an end plate mounted in spaced relation to said face plate, said end plate having an aperture therein, means for connecting a cable harness to said end plate in registry with said aperture, means 20 mounted between said plates including a movable contact, a fixed contact adapted to be engaged by said movable contact and a terminal electrically connected to said fixed contact, and a cup-like casing member formed to engage said face and end plates and completely enclose said contacts and terminal, said casing member having an aperture therein sufficiently large to enable the removal thereof without disconnecting the cable harness. 25
